METHOD OF AND APPARATUS FOR THE
TREATMENT AND USE OF LIQUID FUELSEastman A. Burrows, Chicago, Ill., assignor of
one-half to Thomas D. Campbell, Hardin,
Mont.

Application March 15, 1930. Serial No. 436,014

4 Claims. (Cl. 196—82)

This invention relates to systems for the distillation or other heat treatment of liquid fuel such as hydrocarbon oils by what may be termed waste heat derived from the combustion of a portion of the fuel. In accordance with one form of the invention, oil, which may be of a relatively low grade and may, for example, be a comparatively heavy petroleum, is subjected to distillation, with or without conversion, by the application of the waste heat of the flue gases from a power plant, or similar heat-consuming system, and is then separated into its lighter marketable constituents and its heavier components, the latter being utilized while hot as the fuel for the development of the heat required by the power plant, or other system.

A feature of the invention is in the economy of operation which it affords for the generation of power by heat, or the utilization of fuel for other purposes, such as in the firing of kilns for making brick or the like, or for use in furnaces of various sorts. Heat which would otherwise be largely wasted or used to poorer advantage in systems of the type mentioned may be employed for the purpose of treating a comparatively cheap hydrocarbon oil to form and eliminate certain more valuable components while the heavy, less valuable constituents may be burned to generate the necessary heat. In this way the enhancement in value of the lighter components of the oil will offset in part or in full the initial cost of the crude or other oil used in the process and will in effect supply fuel to the main unit of the system at small or even a negative cost.

A number of factors enter in to make the combination system particularly effective for the purposes mentioned. In the first place the fuel which is burned to generate heat for power or other purposes may be used under favorable conditions so that high efficiency is obtainable. For example, where power is to be generated the boilers may be fired at a comparatively high temperature, which may be well over 2000° F. since the water tubes of such a system are capable of withstanding high temperatures. The flue gases leaving such a system may still be at a temperature as high as 1500° F., or even above, so that they are admirably suited to the distillation of the original fuel. In the second place the immediate transmission to the burners and utilization of the heavier products of the distillation while still hot enables the use of a comparatively heavy residual oil for this purpose, which would practically solidify and be incapable of such use after having been allowed to cool.

Numerous other features and advantages of the invention will appear from the detailed description of the same which will now be given in conjunction with the accompanying drawings, in

Figure 1 is a diagrammatic view showing the inter-relation between the various portions of one type of system to which the invention may be applied.

Figure 2 is a diagrammatic view showing a modified form of furnace which may be advantageously employed in the system disclosed in Figure 1, and

Figure 3 is a diagrammatic view showing a modified arrangement of apparatus as employed in a different type of system.

Referring now to Figure 1, there is disclosed a furnace of more or less conventional form having a fire chamber or combustion zone 10 and an economizer section or convection zone 11. Between the two zones, and in effect forming a screen to divide the one portion of the furnace from the other, there may be advantageously provided a boiler system comprising a plurality of inclined tubes 12 extending between a pair of 80 headers or drums 13 and 14. A fresh supply of water may be introduced into the lower drum through a line 15 while steam may be withdrawn from a dome connected with the upper drum through a line 16.

In the economizer section 11 of the furnace there may be mounted a coil 17 of any suitable construction, being formed preferably of a series of pipe sections joined at their ends by return bends or junction boxes. The diameter and wall 90 thickness of the pipe used in the coil will depend entirely upon the capacity of the unit and the nature of the heat treatment to which oil flowing through the coil 17 is to be subjected. A storage container 18 may be provided to carry a supply of 95 any suitable type of oil, or similar hydrocarbon fuel, which may, if desired, be in the nature of crude oil or other comparatively heavy oil. A pump 19, suitably connected to the supply tank, may serve to force the oil through the coil 17 and discharge it through a line 20 and a pressure 100 regulating valve 21 into a chamber 22. Depending upon the treatment to which it is desired to subject the oil, the latter may be forced through the coil 17 under any desired pressure, 105 ranging from slightly above atmospheric to a substantial pressure of 1,000 pounds, or more. Comparatively low pressure will be employed if it is merely desired to distill the oil without effecting any conversion. However, where it is desired to produce a certain amount of cracking or destructive distillation to effect conversion of some of the heavier constituents into gasoline or similar light components, a higher range, between 110 250 pounds and 1,000 pounds, will preferably be employed. In such a case the regulating valve 21 is preferably set to effect a material reduction in pressure, which may be down to substantially atmospheric within the chamber 22.

60 which:

Lighter vapors which are evolved as a result of the distillation, destructive or otherwise, may be carried over by a vapor line 23 to a condenser coil 24 and the cooled, lighter products may be collected in an accumulator drum 25 having the usual gas and liquid outlets. Heavier components of the oil which are condensed or remain in liquid form in the chamber 22 may be withdrawn through a line 26 and forced under the pressure within the chamber, or by means of a pump 27 through a line 28 to burners 29. Air, or other suitable combustion supporting medium, may be supplied to the burners through a line 30. If desired, automatic means may be provided for controlling the quantity of oil consumed by the burners. For this purpose a valve 31 may be provided in the line 28 and may be controlled in any suitable way by a regulator 32 in the form of a piston or diaphragm affected by the pressure of the steam in the drum 13.

Should it be desired to supply additional heat to the coil 17 in excess of that conveyed by the flue gases passing through the screen of boiler tubes 12, a branch line 33, also fed by the pump 27, may supply oil to burners 34 which receive air, or a similar combustion supporting medium, through a line 35. The burners 34 are preferably situated within a special chamber 36 at the bottom of the convection section of the furnace in such a way that the coil 17 will be shielded from the direct or radiant heat from these burners. A valve 37 may be provided in the line 33 to regulate the quantity of oil supplied to the auxiliary burners. The valve 37 may be automatically controlled by a regulator 38 responsive to a thermostatic unit or thermocouple 39 mounted in the convection section just below the coil 17. In this way additional heat may be supplied to the coil under the direct control of the temperature of the furnace below the coil. If desired, a further control may be effected over the supply of fuel fed from the tank 18 through the coil 17. This may comprise a regulator 40, also operated under control of the temperature-responsive unit 39 and adapted to regulate a valve 41 in the steam line 42 which is connected with the drum 13 and with the pump 19 which forces the oil through the coil 17. In this way the quantity of fuel fed into the system, and from which the supply at the bottom of the chamber 22 is derived, may be regulated directly by the temperatures developed in the furnace. Obviously, the thermocouple or thermostatic unit 39 might be located at some other point, such as at the top of the furnace, if desired, but its location at the point indicated serves to provide a more effective control.

Where the fuel which accumulates in the chamber 22 is of low Baumé gravity and is apt to become viscous, or even semi-solid, upon being allowed to stand for any period of time, it will be found desirable to maintain a certain portion of this oil in continuous circulation. For this purpose a line 43 may be connected to the outlet side of the pump 27 to return any desired portion of the oil withdrawn from the chamber directly back to the same.

In the operation of the unit just described, a temperature well above 2000° F., and even as high as 2500° or 3000° F., may be maintained in the combustion zone 10. The water tubes of the boiler system will be readily capable of withstanding these high temperatures. In such a case the waste flue gases entering the convection zone may still have a temperature between 1500° and 1800° F., which will be sufficient to effect either ordinary

distillation or even destructive distillation of the oil in the coil 17.

It will be found that in the operation of the system to provide just enough heavy oil at the bottom of the chamber 22 to serve as fuel for the power plant, a quantity of lighter components, in the nature of gasoline, kerosene, gas oil and the like, and possibly even lubricating stock, may be taken overhead from the chamber 22, which will be sufficient to practically pay the initial cost of the oil taken from the source of supply 18.

In Figure 2 there is shown a slightly modified form of furnace construction which may advantageously be substituted for the furnace shown in Figure 1. Thus, it may comprise a fire chamber or combustion zone 45 adapted to be fired by a series of burners 46 supplied by oil through a pipe 47 connected with a supply of heavy oil developed at a point in the associated distillation equipment corresponding to the chamber 22. A suitable control valve 48 may be provided in the line 47. Steam may be passed to the burners through a line 49. Regulation of the flame may be effected by a hand-operated or automatically controlled valve 50. Associated with the combustion zone or furnace there may be provided a large heating chamber 51 which is adapted to receive a certain amount of radiant heat and a considerable amount of heat of convection. Within this heating chamber there may be provided any suitable type of boiler system, preferably involving a lower drum 52, an upper steam drum 53, and a series of connecting tubes 54 through which the water passes between the drums. In this type of boiler, considerable space may generally be found between the front and rear banks of tubes and it is proposed to place in this space an oil heating coil 55 of any suitable construction. This coil, as will be clear, will be shielded by the tubes 54 from the direct radiant heat of the burners and will merely receive the milder convective heat of the flue gases. A pump 56, connected to a suitable source of oil supply, may force the oil through the coil 55 under any desired pressure and the heated oil may be passed by a line 58 to an expansion zone, or similar point of the oil distillation system. The system as a whole may, in this case, operate on substantially the same basis as that first described.

In Figure 3 there is shown a system which embodies the principles of the present invention in connection with the treatment of the original liquid fuel or hydrocarbon material in a particular way and the utilization of its heavier components in connection with a brick kiln to supply heat to the latter. Thus, the system may include a kiln 60 adapted to be fired by a series of burners 61, which will raise the temperature within the kiln to a suitable point, preferably between 2500° and 3000° F. Liquid fuel developed within the distillation portion of the unit may be fed to the burners through a line 62. A down-draft arrangement may suitably be provided in connection with the kiln and for this purpose there may be included a laterally extending flue 63 for removing the combustion gases and passing them to a stack suitably located, but not shown. Within the flue may be mounted, in any suitable way, a heating coil 64 adapted to absorb heat from the waste flue gases and impart it to the oil or other medium passed through the coil. For this purpose a pump 65 may serve to draw oil from an annular chamber formed between a tank or drum 66 and an inner circular wall 67 concentric with the tank and forming an inner container there-

in. This oil, after being heated in the coil 64 at any suitable pressure, may be expanded through a pressure regulating valve 68 and passed into a tube 69 which extends into the space within the 5 circular wall 67. This tube preferably has its discharge outlet at some distance from the bottom of the tank and is adapted to discharge the material which is now all, or substantially all, in vapor form against the lowermost of a series of inner baffles 70. A series of co-operating doughnut rings, or outer baffles, 71 may be provided to force the vapors to follow a tortuous path. A certain amount of cracked or other heavy vapors or liquids may be deposited within this inner chamber and will accumulate at the bottom thereof together with the residual material from the fresh oil which is preferably continuously recycled, as will be described. This oil may be withdrawn through a line 72 and may be forced by a pump 10 73 through a central pipe 74 and discharged over the top of the uppermost of the baffles 70. A portion of this oil will then be re-vaporized and the balance will again descend to the bottom of the inner container counter current to the rising vapors. Fresh oil may be introduced into the system by means of a pump 75 and may advantageously be merged in the line 74 with the heavy material which is circulated in the way mentioned. Any light components of this fresh charge will be vaporized and stripped from the same by the rising, heated vapors released at the end of the tube 69. Within the inner chamber only the heavier components will descend to the bottom to be circulated by the pump 73. All of the vapors emerging from the top of the inner chamber pass around a hood or baffle member 76 and into the upper portion of the tank or drum 66. This upper portion of the tank may, if desired, be provided with suitable fractionating or diphlegmating devices, such as bubble trays, baffle members, packing material, or the like. At the top a coil 77 may be provided and may be adapted to receive any suitable form of cooling medium, such as water, or, if desired, the fresh charge 40 may be passed through the coil to effect the double purpose of pre-heating the charge and simultaneously cooling the vapors to maintain a proper endpoint on the product passing out at the top of the column through a vapor line 78. Vapors so withdrawn may be passed through a condenser 79 into an accumulator 80 having the usual gas and liquid outlets. Any condensate which may be knocked back by the coil 77 and the fractionating devices at the top of the column 50 will be directed by the hood 76 into the annular passage between the column or tank 66 and the cylinder 67. It is this material which is withdrawn by the pump 65 and passed through the heating coil 64. It is to be observed that all of this material is clean in the sense that it represents condensate of previously vaporized oil and it is therefore very well suited to destructive distillation or cracking. If the coil 77 is operated at such a temperature as to permit only the 60 relatively light vapors, such as gasoline, to pass through the line 78, it may be found desirable to draw off a certain amount of the material within the annular chamber surrounding the cylinder 67 through a line 81, either continuously or intermittently. This material may be either in the nature of kerosene, gas oil, lubricating stock, or the like.

While several admirable embodiments of the invention have been set forth in considerable detail in the foregoing, it is to be understood that numerous changes may be made without departing from the general spirit of the invention. Features employed in connection with one of the 80 illustrated embodiments of the invention may readily be employed in connection with features of another of the embodiments. Various forms of heat-consuming systems other than power plants and brick kilns may be substituted for the latter. It is particularly advantageous, however, to apply the liquid fuel treating system to a furnace system, or the like, which is operated at relatively high temperatures so that the flue gases from the latter may be discharged at a relatively 85 high temperature. The terms employed in the foregoing description are to be considered merely as setting forth the nature of the invention and not as imposing any limitations on its scope.

What I claim is:

1. A cyclic process for the treatment and use of a liquid fuel which comprises continuously introducing said fuel into a heating zone to effect partial distillation thereof, removing lighter components resulting from said distillation, passing 90 heavier components to burners in a furnace associated with a primary heat utilization system for heating material other than said fuel maintained at a temperature above 2000° F., and cyclically passing intermediate components resulting from said distillation into heat exchange with the flue gases from said furnace at a temperature below 1800° F. and back to said heating zone.

2. Apparatus for distilling oil which comprises an outer chamber, an inner chamber, diphlegmating means at the top of said outer chamber, means for feeding fresh oil into said inner chamber, a heating coil, means for withdrawing oil from said outer chamber and passing the same through said heating coil, means for conveying 100 said heated oil to said inner chamber to evolve vapors therein, and means for directing condensate from said diphlegmating means to said outer chamber.

3. A process for the treatment and use of a 110 liquid fuel which comprises subjecting the fuel to distillation, separating the products into lighter and heavier components, passing a portion of the heavier components while hot to burners in a combustion zone associated with a primary heat utilization system for heating material other than said fuel, utilizing the waste heat of the flue gases from said zone for effecting said distillation, and passing a regulated portion of said 115 heavier components to auxiliary burners to aid 120 said distillation.

4. In apparatus of the class described heating means comprising a combustion zone having burners therein and an economizer section, primary heat absorbing means between said combustion zone and economizer section, a coil in said economizer section, means for passing oil through said coil to effect distillation thereof, means for passing material other than oil through said heat absorbing means, means for 130 separating the oil into lighter and heavier components, means for passing a portion of said heavier components while hot to said burners, auxiliary burners adapted to supply heat to said economizer section, and means for conveying a 135 portion of said heavier components to said auxiliary burners.

EASTMAN A. BURROWS.
